(57) CLAIM

I claim the ornamental design for a pocket for a garment, as shown and described.

DESCRIPTION

FIG. 1 is a perspective view of a pocket for a garment showing my new design; and,
